UNITED STATES PATENT OFFICE.

ALFRED WILLARD BENSON, OF SAN BERNARDINO, CALIFORNIA.

WELL-PIPE CUTTER.

SPECIFICATION forming part of Letters Patent No. 299,331, dated May 27, 1884.

Application filed March 3, 1884. (No model.)

To all whom it may concern:

Be it known that I, ALFRED W. BENSON, of San Bernardino, San Bernardino county, California, have invented a new and Improved 5 Well-Pipe Cutter, of which the following is a full, clear, and exact description.

The object of my invention is to provide a new and improved device for making longitudinal slots through the pipes used in Artesian wells, &c., at any point below the surface of the ground, for the purpose of admitting any stream or streams of water, &c., that may have been passed in boring the well, whereby the yielding capacity of the well is 15 increased.

The invention consists in a cutter-roller held in a forked piece, in which another forked piece is held which is provided with diagonal slots, through which the pintle of the cutter-roller passes. Means are provided to raise or lower the inner forked part, thereby causing the cutter-roller to project more or less. The device is then worked up and down and cuts a slot 20 in the pipe.

Reference is to be had to the accompanying drawings, forming part of this specification, in which similar letters of reference indicate corresponding parts in all the figures.

Figure 1 is a side view of my improved 30 well-pipe cutter. Fig. 2 is an edge view of the same. Fig. 3 is an enlarged longitudinal sectional view of the swivel-joint; and Fig. 4 is an enlarged sectional plan view on the line *x*-*x*, Fig. 1.

In the lower end of a forked piece, A, a sharp-edged cutting-roller, B, is pivoted, the pintle C of which roller passes through inclined slots D in the shanks of a forked piece, E, held between the shanks of the forked 35 piece A. A screw, F, projecting upward from the top of the forked piece E, is screwed through an internally-threaded sleeve, G, held to turn in the ring H, formed on the upper end of the forked piece A. On the upper 40 end of the sleeve G a swivel-piece, J, is screwed and fastened, on the upper end of which a screw, K, is formed for attaching the working-rod. In one edge of the forked piece E anti-friction rollers L are pivoted, and to 45 the lower end of the forked piece E two bow-springs, M, are fastened.

The operation is as follows: The instrument is forced down in the well-pipe, and the

springs M prevent the part E from turning. If the swivel part J is turned, the sleeve G is 55 turned with it and the part E is moved upward, thereby causing the cutter-roller B to project from the edge of the part A. The entire device is then worked up and down, thereby causing the roller B to cut a vertical 60 slot in the pipe, which slot may be made of any desired width by turning the device more or less on its longitudinal axis. After the desired slot or slots have been cut, the swivel part J is turned in the inverse direction to 65 cause the part E to move downward, thereby withdrawing the cutting-roller in between the shanks of the part A.

Having thus described my invention, I claim as new and desire to secure by Letters Patent— 70

1. In a well-pipe cutter, the combination, with the forked part A, of the forked part E within it, the cutter-roller B, pivoted in the lower part of the part A, the pintle C, passing through diagonal slots D in the part E, 75 and of means for adjusting the part E higher or lower in the part A, substantially as herein shown and described.

2. In a well-pipe cutter, the combination, with the forked part A, of the forked part E 80 within it, the cutter-roller B in the lower end of the part A, the pintle of the roller passing through diagonal slots D in the part E, means for adjusting the part E higher or lower in the part A, and of the springs M on the lower 85 end of the part E, substantially as herein shown and described.

3. In a well-pipe cutter, the combination, with the forked part A, of the forked part E, 90 having diagonal slots D, the cutter-roller B, held in the part A, the springs M on the lower end of the part E, and the rollers L on the part E, substantially as herein shown and described.

4. In a well-pipe cutter, the combination, 95 with the forked part A, of the forked part E within the same, and provided with diagonal slots D, the cutter-roller B in the lower end of the part A, the internally-threaded sleeve G, held to turn in the upper end of the part 100 A, and of the swivel J, secured to the sleeve G, substantially as herein shown and described.

ALFRED WILLARD BENSON.
